UNITED STATES PATENT OFFICE

2,432,104

SYSTEM OF LIGHT MODULATION

Elihu Craig Thomson, Boston, Mass., assignor to
 Photoswitch, Inc., Cambridge, Mass., a corporation of Massachusetts

Application March 10, 1945, Serial No. 582,112

3 Claims. (Cl. 250—41.5)

1

The present invention relates to systems requiring modulation of the light emission from electric light sources, and more particularly to an electric circuit incorporating arrangements for periodically interrupting the light of an electric lamp that affects a light-responsive device.

It is the main object of the invention to provide an electric circuit which in an extremely simple and reliable manner modulates the output of an electric lamp which controls light-sensitive electric apparatus.

It is often desirable to make use of a light source whose emission is subject to periodical fluctuations which are large enough to affect light-sensitive devices such as phototubes.

One of the reasons making such a light source desirable is that of using it for the control of a photoelectric device which is responsive only to light of a given frequency, thus eliminating interference from other light sources in the vicinity of the phototube. Another reason to use fluctuating light sources is the well-known fact that proper amplification of the output of phototubes can best be accomplished by means of alternating current amplification circuits. Various devices have been proposed to obtain a pulsating output of phototubes. One of these is the so-called mechanical light chopper which usually consists of a slotted disk rotated in front of the phototube. Other ways of accomplishing similar results involve the use of auxiliary photocells and light sources in an oscillating circuit, the use of Kerr cells and light-polarizing apparatus, or the use of self-oscillating phototube circuits. All these arrangements have disadvantages such as movable mechanical parts, electron discharge devices added to already rather complex electronic amplification circuits, inherently uncertain operation, and introduction of undesirable higher harmonics.

The arrangement according to the present invention avoids such difficulties by incorporating a purely electric arrangement in the supply circuit of the light source which excites the photosensitive apparatus.

Although the above-indicated use of the arrangement according to the invention in cooperation with photoelectric circuits is especially beneficial, it is understood that the effect obtained may be of use in other environments, wherever a fluctuating light source is desirable.

These and other objects and aspects will be more fully apparent from the following description of a practical embodiment illustrating the general character of the invention. The description refers to a drawing in which

2

Fig. 1 is a circuit diagram of a practical embodiment of the invention; and

Fig. 2 is a diagram illustrating the operation of the device according to Fig. 1.

Fig. 1 shows at L a transformer whose primary L_p is supplied from an alternating current source indicated by terminals A, B. This source will in most instances be a standard 60-cycle alternating current line but it is understood that alternating or fluctuating current sources of different frequencies can be employed and that frequency modifying devices such as frequency reducing or multiplying arrangements may be inserted between the available alternating current source and the circuit according to the invention.

The secondary L_s of transformer L is connected to a rectifying circuit which, in the present example that employs a standard incandescent lamp furnishing light sufficient for operating a stand-

ard phototube, may consist of two standard, type 3576, rectifier tubes T_1 and T_2 connected in parallel, and having heaters h , cathodes k and anodes a . The heaters h may be supplied from a tap t of secondary L_s through a voltage-reducing and current-limiting resistor R_1 . The cathodes k are connected at d to terminal b of secondary L_s and to the heater circuit. The anodes a lead through load-equalizing resistors R_2 , R_3 , R_4 , R_5 to one terminal of light source 10 in the present instance a standard 115 volt 50 watt incandescent lamp, whose other terminal is connected to terminal a of secondary L_s .

The light source is preferably an incandescent lamp but, in combination with suitably selected photoelectric circuits, any radiation source may be employed which is fundamentally slow heating to such a degree that the radiation loss between the peaks of the conventional alternating current source would provide a light modulation

insufficient for purposes of efficiently operating the device which is to be controlled by the radiation source.

The light source 10 is arranged to illuminate in suitable, conventional manner a phototube P which forms part of an amplification and control network indicated at N. In accordance with the purpose of the invention, this network will be one which is especially suited for alternating current operation of a sensitivity adapted to the range of variation of radiation as provided in accordance with the present invention, and it may include arrangements for discriminating between different frequencies.

The arrangement according to Fig. 1 operates as follows.

The alternating current furnished by secondary L_s has the wave shape indicated in Fig. 2 by dotted lines below, and in full lines above the zero axis. Since the lamp filament is heated by current flowing in either direction, the light source would have a modulation frequency of 120 cycles, if it were connected directly to the transformer L . With a light source of the above-indicated characteristics, this modulation is not sufficiently distinct to be detected in ordinary photoelectric circuits, because the filament does not sufficiently cool to affect the light radiation appreciably in the short time during which no current is flowing.

The rectifying circuit according to the invention eliminates in known manner the half cycles shown in dotted lines in Fig. 2 and provides current of the wave shape indicated with a heavy line. The current intensity is zero during periods essentially corresponding to the eliminated half cycle and these periods are of sufficient duration to permit the filament to cool between the current peaks, thus reducing the light radiation from the filament appreciably between these peaks. The modulation thus produced is sufficient for detection by the conventional phototube circuit of the above-indicated nature, intended for alternating current operation and, if desired, for frequency discrimination.

It is understood that the rectifier system can be connected in various ways for example for shunting one half wave series around the light source.

It will be evident that apparatus of this type can be used not only for detecting persons or articles passing between light source 10 and photo tube P , but that any detecting, light absorbing or otherwise modifying device can be inserted between lamp and light sensitive element.

It should be understood that the present disclosure is for the purpose of illustration only and that this invention includes all modifications and equivalents which fall within the scope of the appended claims.

I claim:

1. Apparatus for providing a regularly modulated light flux, comprising: an alternating current supply, a light source adapted to maintain a slightly varying light output while supplied with current impulses at the intervals of the half wave periods of said supply but to furnish a fluctuating light output while supplied with current impulses at intervals of alternate half wave periods of said supply, a transformer having a primary connected to said supply and a secondary with two terminals, electron discharge means having cathode means and anode means and adapted to pass current in one direction, and connections including said light source and forming a circuit from one of said terminals through said cathode and anode means to the other terminal, the unidirectional conductivity of said discharge means causing current impulses to be supplied to said light source at alternate half wave periods of said supply and hence causing

said light source to furnish light energy fluctuating at the supply frequency.

2. Apparatus for providing a regularly modulated illumination comprising in combination: an alternating current supply; an incandescent lamp having a resistance filament adapted to maintain a slightly varying light output while supplied with current impulses at the intervals of the half wave periods of said supply but adapted to furnish, while supplied with current impulses at intervals of alternate half wave periods of said supply, a light output fluctuating periodically at the supply frequency; a half wave rectifier; and a transformer having a primary connected to said supply and a secondary, said half wave rectifier and said lamp being connected in a series circuit; said half wave rectifier passing only alternate half wave impulses from said supply to said lamp and thereby causing said lamp to furnish a light output fluctuating periodically at the supply frequency.

3. Photoelectric apparatus comprising in combination: an operative circuit responsive substantially only to signals of a predetermined frequency and including a light-sensitive actuating member; and a controlling circuit including an alternating current supply of substantially said predetermined frequency, an incandescent lamp having a resistance filament arranged for illumination of said light sensitive actuating member, said filament being adapted to maintain a slightly varying light output while supplied with current impulses at substantially double said predetermined frequency, but adapted to furnish, while supplied with current impulses at said predetermined frequency, a light output fluctuating periodically at said predetermined frequency, a half wave rectifier, and a transformer having a primary connected to said supply and a secondary; said secondary, half wave rectifier and said lamp being connected in a series circuit; whereby said half-wave rectifier passes only alternate half wave current impulses from said supply to said lamp and hence causing said lamp to furnish light fluctuating periodically at said predetermined frequency to said light-sensitive actuating member.
